O. W. Schulz,

UNITED STATES PATENT OFFICE.

OTTO W. SCHULZ, OF DENVER, COLORADO.

COLLAR-BUTTON.

1,218,483.

Specification of Letters Patent.

Patented Mar. 6, 1917.

Application filed April 14, 1916. Serial No. 91,230.

To all whom it may concern:

Be it known that I, OTTO W. SCHULZ, a citizen of the United States, residing at Denver, in the county of Denver and State of Colorado, have invented new and useful Improvements in Collar-Buttons, of which the following is a specification.

This invention is an improved collar button, the object of the invention being to provide an improved device of this character which is extremely cheap and simple in construction, which may be readily used, which enables the collar to be readily adjusted or removed, which offers no obstructions to the slipping of the tie, which does not change the shape of the button hole in either the collar or the neck band of the shirt, which cannot become casually unfastened, which cannot turn over in the neck band and gouge the neck, which prevents the tie from slipping up on a standing or full dress collar, which can be adjusted according to the width of the neck band on which it is used and which prevents pressure on the back of the neck and which is also extremely durable.

The invention consists in the construction, and arrangement of devices hereinafter described and claimed.

In the accompanying drawings:—

30 Figure 1 is a perspective view of a collar button constructed and arranged in accordance with my invention.

Fig. 2 is an end elevation of the same in use, a portion of the neck band of a shirt and also a portion of the collar being shown in section.

In the embodiment of my invention, I provide a plate 1 which may be made of sheet metal or other suitable material and which is provided, at points spaced from its center with vertical slits 2 of suitable length and which extend down from its upper side. The portion 3 between the slits is offset outwardly and is bent in inverted U form to provide an inner arm 4 which is connected at its lower end to the plate and is spaced

from the plane of the plate, an outwardly extended shoulder 5 at the upper end of said inner arm and a downwardly extending arm 6 at the outer side of said shoulder and the lower end of which is rounded and slightly out-turned as at 7. A lug 8, which is struck up integral with the plate, from an opening 9 in the shoulder 5, projects upwardly from and is in line with the offset 4 and mid-way between the ends of the shoulder 5.

To insert the button in the neck band 10 of the shirt, the loose outer flap 11 of the neck band is turned upwardly, the hook or arm 6 is put through the button hole, the plate or base 1 is turned inwardly to arrange it between the folds of the neck band, the upper side of the button hole is engaged behind the lug and the device is then pushed upwardly, the offset 4 engaging the neck band above the button hole as shown in Fig. 2.

The button hole of the collar is engaged with the hook arm 6, and the upper side of the button hole of the collar is caused to bear on the shoulder 5 which prevents the collar from working downwardly.

Having described the invention, what is claimed is:

The herein described collar button comprising a plate, and having a hook comprising an inner arm connected at one end to the plate and spaced from the plane of the plate, an outwardly extending shoulder at the opposite end of said inner arm, an arm at the outer side of said shoulder and opposite the inner arm and a lug which extends from the shoulder and which lies in the plane of said inner arm.

In testimony whereof I affix my signature in presence of two witnesses.

OTTO W. SCHULZ.

Witnesses:

MORRIS H. WEINBERGER,
